UNITED STATES PATENT OFFICE.

JAMES B. NEWSOM, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed December 15, 1923. Serial No. 680,808.

To all whom it may concern:

Be it known that I, JAMES B. NEWSOM, a citizen of the United States of America, residing at Brooklyn, in the county of Kings, 5 State of New York, have invented certain new and useful Improvements in Telephone Systems, of which the following is a full, clear, concise, and exact description.

This invention relates to telephone systems, and more particularly, to improvements in the impulse sending circuits used in establishing connections between manual and automatic exchanges.

This invention is adapted for use in systems in which telephone lines terminating at a private branch exchange switchboard may be extended by means of operators' link circuits through trunk circuits and automatic switches to telephone lines terminating in an 10 automatic exchange. In such systems the private branch exchange operator is provided with an impulse sender that may be associated with a link circuit and operated to transmit impulses to select the desired 15 line. The control of the switches is effected by the aid of an impedance element bridge across the talking conductors of the link and trunk circuits the moment the impulse sender is associated therewith, and this impedance element is short circuited during 20 the transmission of impulses.

An object of this invention is to provide an improved system of this character by means of which the introduction of the impedance element across the talking conductors will not disturb the control of the 25 automatic switches.

Another object of the invention is to maintain the impulse contacts of the sender short-circuited while the sender is in non-operated 30 position and connected to the link circuit.

To attain these objects in accordance with one feature of this invention, a relay arrangement is provided whereby a resistance 35 is momentarily introduced in parallel with the impedance element when bridged across the conductors to reduce the inductive effect on the impulse responsive relays used in circuits of this type for controlling the operation of the automatic switches.

A further feature is the provision of a relay arrangement whereby a short-circuit of the impulse contacts and the impedance element are both removed from across the talk-

ing conductors when the impulse sender is 55 actuated.

For a more complete understanding of this invention, reference should be made to the following description and the accompanying drawing in which Fig. 1 illustrates one embodiment of the invention as applied to a private branch exchange system. Fig. 2 shows a diagrammatic form the inclusion 60 of a resistance in the impulse circuit and Fig. 3 represents the current values incidental thereto.

As shown in the drawings a telephone line A terminates at a private branch exchange where it may be connected to the link circuit B in any well-known manner. The calling end of the link circuit may be connected with the trunk circuit C shown diagrammatically and extending to the automatic exchange D at which are provided the usual selector and connector switches, 70 also shown diagrammatically, for effecting connections between the trunk circuit and telephone lines such as E terminating at the automatic exchange.

The nature of the invention is such that a clear understanding will be obtained from a description of the invention as shown in the drawing while tracing a call from the calling subscriber on line A to the wanted subscriber on line E, and it will be so described. 80

Assuming that the subscriber on line A has initiated a call and the answering end of the link circuit B associated therewith in any well-known manner, the operator actuates the listening and dialing key 5 connecting her telephone set in circuits as follows: battery, lower right-hand winding of repeating coil 2, lower operated contacts of key 5, through the operator's telephone set 1 (not shown in detail), left-hand armature and back contact of relay 20, inner upper actuated contacts of key 5, upper right-hand winding of induction coil 2 to ground. The operator may now converse with the calling subscriber through repeating coil 2 and line A to ascertain the number of the line with which connection is desired. Assuming that connection is desired with the station on line E terminating at automatic exchange D, the operator inserts calling plug 6 of the link circuit B into jack 7 of trunk circuit C and thereby causes circuit connections to be made as is well known in the 95 100 105

art to connect an impulse responsive relay such as 10 directly through the talking conductors of the link circuit to battery at repeating coil 2. The circuit for relay 10 may 5 be traced as follows: battery, right-hand winding of relay 10, tip contacts of jack 7 and plug 6, upper make-before-break contact of relay 12, upper right-hand winding of induction coil 2 to ground, and a similar 10 circuit from battery, lower right-hand winding of induction coil 2, lower make-before-break contacts of relay 12, ring contacts of plug 6 and jack 7, left-hand winding of relay 10 to ground. These circuits operate the impulse 15 responsive relay 10 which thereby prepares the circuit of the selector switch for the reception of impulses from the impulse sender 15, over a circuit hereinafter to be traced.

20 The operation of the sender 15 to effect a connection with the subscriber's line E will now be described. The sender 15 may be of any well-known construction provided with impulse contacts 16 and off-normal contact 17. When the operator moves the 25 sender from normal an energizing circuit for relay 20 is completed as follows: battery, winding of relay 20, off-normal contact 17 to ground. Relay 20, in operating, 30 disconnects the operator's telephone set 1 from the talking connection to the calling subscriber, at its left-hand armature and back contact and at its outer right-hand armature and front contact closes a circuit 35 including the resistance 21 in parallel with a high impedance element or retardation coil 22 into a circuit hereinafter to be described for holding the impulses responsive relay 10 in operated position. The connection of contact 17 to ground also completes 40 an energizing circuit for relay 12 as follows: battery, winding of relay 12, upper actuated contacts of key 5, make-before-break contacts of relay 19, off-normal contact 45 17 to ground. The operation of relay 12 closes a circuit for relay 19 as follows: battery, winding of relay 19, lower outer armature and front contact of relay 12 to ground. Relay 19, in operating, closes a 50 locking circuit for relay 12 as follows: battery, winding of relay 12, upper actuated contact of key 5, a make-before-break contact and armature of relay 19 to ground. The operation of relays 20 and 12 closes a 55 circuit for slow-to-release relay 23 as follows: battery, winding of relay 23, inner right hand armature and front contact of relay 20, lower outer armature and front contact of relay 12 to ground. It should be 60 noted here that the operation of relay 12 which occurs slightly after the operation of relay 20 also breaks the circuit for relay 10 through the repeating coil 2 and completes the holding circuit for relay 10 in conjunction 65 with contacts of relays 23 and 20. This

circuit may be traced as follows: battery, right-hand winding of relay 10, tip contacts of jack 7 and plug 6, a make-before-break contact and upper armature of relay 12, retardation coil 22 and resistance 21 in parallel, the closed outer right-hand armature and front contact of relay 20 and left-hand armature and front contact of relay 23, impulse contacts 16 and make-before-break contacts of relay 24 in parallel, lower inner armature and front contact of relay 12, ring contacts of plug 6 and jack 7, left-hand winding of relay 10 to ground. It should be noted that this circuit, due to the fact that retardation coil 22 and resistance 21 are in parallel, prevents relay 10 from deenergizing as current through these elements builds up sufficiently fast to hold relay 10 energized and thus the breaking of the direct connection to battery at repeating coil 2 will have no effect on the relay 10. The operation of relay 23 also completes an energizing circuit for relay 24 as follows: battery, winding of relay 24, right-hand armature and front contact of relay 23, off-normal contact 17 to ground. The operation of relay 24 removes at its make-before-break contacts the short circuit for the impulse contacts 16 and at its armature short circuits the resistance 21 and retardation coil 22 and extends the impulse circuit for relay 10 directly under control of the impulse contacts 16. Relay 24 is made slow to operate so that the short circuit for the impulse contact 16 will not be removed until the operator actually is ready to start the selecting operations and any slight disturbance of the impulse sender while the conversation between the subscriber and the operator takes place will not have any effect on the impulse circuit for relay 10. On return of the sender to normal the circuit for the impulse responsive relay 10 is interrupted a number of times equal to the first digit of the number desired and the selector switch is accordingly set in the usual manner well-known in the art of automatic telephony and the second series of impulses will, in a similar manner, operate the connector to extend the connection to the wanted subscriber on line E.

It is, of course, necessary to maintain relay 10 operated during the intervals between series of impulses, after the sender operations are completed and while the dialing key is still operated. This is accomplished by including the retardation coil 22 in a shunt across the talking conductors, that is, at the moment the sender is returned to normal direct connection for relay 10 is broken and the retardation coil 22 inserted in its place. This might ordinarily, due to the high impedance of this coil, cause a release of the relay 10. In order to prevent this, a temporary path through the resistance 125

21 in parallel with the coil 22 is provided so that the current through the coil will have time to build up sufficiently to hold relay 10 when resistance 21 is later removed.

6 The functions of the relays for accomplishing this purpose will now be described.

At the return of the impulse sender 15 to normal the ground at off-normal contact 17 is removed causing relays 20 and 24 to release. Relay 24, in releasing, removes the direct connection for relay 10 to the impulse contact 16 and short-circuits these contacts as previously described and also includes the retardation coil 22 and resistance 21 in parallel

18 in a bridge across the conductors over the following circuit: battery, right-hand winding of relay 10, tip contacts of jack 7 and plug 6, an upper make-before-break contact and armature of relay 12, retardation coil

20 22 and resistance 21 in parallel, left-hand armature and front contact of relay 23, make-before-break contacts of relay 24 and impulse contacts 16 in parallel, lower inner armature and a make-before-break contact

25 of relay 12, tip contacts of plug 6 and jack 7, left-hand winding of relay 10 to ground. This circuit, therefore, provides a low resistance path for the current for relay 10 so that it will not be released, but receive at

30 once sufficient current to prevent it from being in any way effected by the changeover. However, this path is merely temporarily maintained as relay 20 in releasing breaks at its inner right-hand armature and front

35 contact the circuit for relay 23 and at its outer right-hand armature and front contacts breaks one connection for resistance 21. When relay 23 releases the other connection for resistance 21 is opened at the left-hand

40 armature and front contact of this relay so that now only the retardation coil 22 is bridged across the conductors to maintain relay 10 energized. At this time, however, due to the slow release of relay 23, the circuit through retardation coil 22 has been suffi-

45 ciently built up to hold relay 10 energized.

It should be noted that relays 19 and 12 are still maintained energized and will not release until the dialing key 5 is returned to

50 normal. When the dialing operations are completed the operator releases key 5 and all relays including relays 12 and 19 are released. The release of relay 12 causes the circuit for relay 10 to be removed from the

55 path through the retardation coil 22 and ex-

tended as previously traced through the talk-

ing conductors to battery at repeating coil

2. The release of key 5 thus removes the im-

50 pulse sender 15, the operator's telephone

set 1 and the associated relay arrangement

from the link circuit. The impulse sender may then be used for establishing con-

nections at other link circuits. When the connection is completed to telephone line

65 E, the subscriber on this line is rung auto-

matically in the usual manner at the automatic exchange and when the subscriber on this line answers the circuit is completed for conversation between the subscribers on lines A and E. In case the operator has not by 70 then released key 5 conversation will take place over condensers 25 and 26 as shown through contacts of relay 23, for it will be remembered that in such a case relay 12 is still operated. The operator may release 75 the connection at the end of the conversation in the usual manner employed in manual telephone exchange systems.

The diagram shown in Fig. 2 illustrates in simplified form the arrangement for the inclusion of resistance 21 in parallel with retardation coil 22, in the circuit for relay 10 and serves in connection with the curves shown in Fig. 3 to show how sufficient current is immediately supplied for relay 10 to 80 maintain it energized when contacts 24' are open. If line 30, Fig. 3, is considered as representing the value of the current passing through relay 10 when contacts 24' are closed and line 31 represents the value of 85 the current at which the relay 10 will release its armature, line 32 may represent the value of a current for relay 10 when contacts 23' are closed and contacts 24' are open. This later current which is that passing 90 through resistance 21 and retardation coil 22 in parallel is, therefore, sufficient to hold the relay 10 energized, until the current through retardation coil 22 is built up to such a value as represented by line 35 as to permit relay 95 10 to be held when the resistance 21 is removed by the opening of contacts 23'. If, on the other hand, resistance 21 was not included in this circuit at the time contacts 24' are open, the current through retardation 100 coil 22 would build up approximately in accordance with the curve 33 and relay 10 would therefore be permitted to release for a period equal to the distance 34 and consequently disturb the connection established 105 by the operation of this relay. It is evident then that the inclusion of resistance 21 in parallel with the retardation coil 22 for a short interval will at once establish the required circuit conditions for holding relay 110 10 energized and thus permit the inclusion of retardation coil 22 in this circuit between series of impulses or after the setting up operation is completed without disturbing the control circuit.

What is claimed is:

1. In a telephone system, an impulse circuit, an impulse sender therefor, an impedance element in said circuit, means for short-circuiting and impedance during a desired period, and means for including a resistance in parallel with said impedance element for a short interval after the short-circuit has been removed.

2. In a telephone system, an impulse cir-

130

cuit, an impulse sender therefor, an impedance element in said circuit, means operated by the actuation of the sender for short-circuiting said impedance during a 5 desired period, and means controlled by the sender for including a resistance in parallel with the impedance for a short interval after the short-circuit has been removed.

3. In a telephone system, an impulse circuit, an impulse sender therefor, an impedance element normally in said circuit, a resistance element normally disconnected from said circuit, and means for short-circuiting said impedance during a desired period, and 10 15 for including said resistance in parallel with said impedance for a short interval after the short-circuit has been removed.

4. In a telephone system, an impulse circuit, an impulse sender therefor, an impedance element in said circuit, means operated by the actuation of the sender for short-circuiting said impedance during a desired period, and means operated by the actuation 20 25 and release of the sender for including a resistance element in parallel with the impedance element for a short interval after the release of the sender.

5. In a telephone system, an impulse circuit, an impulse sender therefor, an impedance element in said circuit, a resistance element, means responsive to the actuation of the sender for short-circuiting the impedance element during a desired period, and means comprising a relay arrangement 30 35 controlled by the sender for including said resistance in parallel with the impedance for a short interval after the sender is released.

6. In a telephone system, an impulse circuit, an impulse sender therefor, two resistance elements, one of which is included in said circuit while the sender is in normal position, and means for short-circuiting said elements while the impulse sender is 40 45 in actuated position and for including the other resistance element in said impulse circuit for a short interval after said sender has returned to normal position.

7. In a telephone system, an impulse circuit, an impulse sender therefor provided with impulse contacts and off-normal contacts, an impedance element in said circuit in series with the impulse contacts of the sender, a resistance element, a relay responsive to interruptions in the impulse circuit by said impulse contacts, means for short-circuiting said impedance element controlled by said off-normal contacts when actuated, and means controlled by said off-normal 50 55 60 65 contacts when actuated for including said resistance element in parallel with said impedance element a short interval after said off-normal contacts are released in normal position to prevent the impulse responsive relay from deenergizing after the removal

of the short-circuit by said release of the the off-normal contacts.

8. In a telephone system, an impulse circuit, an impulse sender therefor, an impedance element in said circuit, a resistance, means for short-circuiting said impedance element during a desired period, means for including the resistance in parallel with said impedance element a short interval after the short-circuit has been removed, and means 70 75 for normally short-circuiting the impulse contacts of the sender and for removing said short-circuit during the operation of the sender.

9. In a telephone system, an impulse circuit, an impulse sender therefor, an impedance element in said circuit, a resistance, means for short-circuiting said impedance element during a desired period, means for including the resistance in parallel with said impedance element a short interval after the short circuit has been removed, and means 80 85 controlled by the sender for normally short-circuiting the impulse contacts of the sender and for removing said short circuit while the sender is actuated.

10. In a telephone system, calling and called subscribers' lines, an operator's telephone set adapted to be connected with said calling subscriber's line, an impulse circuit normally connected to said telephone set, an automatic switch, an impulse sender in said circuit, an impulse responsive relay in said impulse circuit for the operation of said switch to connect the impulse circuit with a wanted subscriber's line, means for disconnecting said calling subscriber's line and operator's telephone set from said impulse circuit while the impulse sender is operated, an impedance element normally shunted across the conductors of said impulse circuit, a resistance, and means for short-circuiting said impedance during the 90 95 100 105 operation of the sender and for including the resistance in parallel with the impedance in said impulse circuit a short interval after the sender is released.

11. In a telephone system, calling and called subscribers' lines, an operator's telephone set adapted to be connected with said calling subscriber's line, an impulse circuit normally connected to said telephone set, an automatic switch, an impulse sender in said circuit, a trunk circuit adapted to be connected to said impulse circuit and an impulse responsive relay in said trunk circuit for the operation of said switch to connect the trunk circuit to a wanted subscriber's line, means for disconnecting said calling subscriber's line and operator's telephone set from said impulse circuit while the impulse sender is operated, an impedance element normally shunted across the conductors of said impulse circuit, a resistance, and means for short-circuiting said imped- 110 115 120 125 130

ance during the operation of the sender and for including the resistance in parallel with the impedance in said impulse circuit a short interval after the sender is released.

- 5 12. In a telephone system, a telephone line, an operator's telephone set adapted to be connected thereto, an impulse circuit connected to said operator's telephone set, an impedance element bridged across the conductors of said impulse circuit, a resistance, an impulse sender in said impulse circuit, means controlled by the operation of said sender for short-circuiting said impedance, for disconnecting the telephone line and operator's set from the impulse circuit during the operation of the sender and for including the resistance in parallel with the impedance for a short interval after the release of the sender.
- 10 13. In a telephone system, telephone lines, an operator's telephone set adapted to be connected to one of said lines, an impulse circuit, a trunk circuit, an automatic switch, an impulse responsive relay for the control 25 of said switch to connect to another of said lines, an impulse sender having impulse contacts in said impulse circuit, an impedance element across the conductors of said impulse circuit, a resistance element, and means under control of said sender for disconnecting the operator's telephone set from the impulse circuit, for short-circuiting the impedance element and connecting the impulse circuit to the trunk circuit while the 30 sender is in operated position, and for including the resistance in parallel with the impedance for a short interval after the return of the sender to normal.

14. In a telephone system, an impulse circuit, an impulse sender having impulse contacts in said impulse circuit, an impedance element in said circuit, a resistance element, means controlled by the sender operations for opening a short-circuit in said impulse 45 circuit across the impulse contacts for closing a short-circuit for the impedance across the conductors of the impulse circuit while the sender is in operated position and for including the resistance in parallel with the 50 impedance for a short interval after the sender has returned to normal.

15. In a telephone exchange system, an impulse circuit, an impedance element in said circuit, an impulse sending device having

its impulse contacts in said circuit, an impulse responsive relay in said circuit, means responsive to the actuation of the sender for removing the impedance element from said circuit and for closing a direct path for said impulse contacts to said impulse responsive relay, a resistance element, means under control of the sender for including for a short interval after the return of the sender to normal the resistance element in parallel with the impedance elements to provide a low impedance path for maintaining the impulse responsive relay operated after the direct path has been removed due to the release of the sender.

16. In a telephone system, a relay in series with an impedance, said impedance being of a value insufficient to cause the immediate energization of said relay but sufficient to maintain said relay energized after its energization, means for short circuiting 75 said impedance, and means for shunting said impedance temporarily incident to the removal of said short-circuit by said first means.

17. In a telephone system, a relay in series with an impedance, said impedance being of such a value that it will not alone permit the immediate energization of said relay therethrough but will hold it if once energized, means for short-circuiting said impedance to permit the relay to be energized, and means for shunting said impedance for a short interval after the short circuit has been removed to allow said relay to be maintained energized through said impedance alone.

18. In a telephone system, a relay in series with an impedance, said impedance being of such a value that it will not alone permit the immediate energization of said relay therethrough but will hold it if once energized, means for short-circuiting said impedance to permit the relay to be energized, and means for shunting said impedance for an interval of time after the short circuit has been removed to permit the current therethrough to increase to such an extent as to hold the relay energized.

In witness whereof, I hereunto subscribe my name this 5th day of December A. D., 105 1923.

JAMES B. NEWSOM.
